(57) **CLAIM**

The ornamental design for a retrofit fence panel, as shown and described.

DESCRIPTION

FIG. 1 depicts an exploded, front perspective view of a retrofit fence panel with mounting bolts in accordance with the present invention.

FIG. 2 depicts a rear perspective view of the retrofit fence panel thereof.

FIG. 3 depicts a front view of the retrofit fence panel, shown without the mounting bolts and fence for ease of illustration.

FIG. 4 depicts a rear view of the retrofit fence panel thereof.

FIG. 5 depicts a front perspective view of the retrofit fence panel thereof; and,

FIG. 6 depicts another front perspective view of the retrofit fence panel, in a position of use on a fence.

The broken lines in the drawings depicting a fence illustrate environmental subject matter that forms no part of the claimed design.

1 Claim, 6 Drawing Sheets
